J. NASH,
DRAWING INSTRUMENT,
APPLICATION FILED DEC. 3, 1917.

1,315,679.

Patented Sept. 9, 1919.

UNITED STATES PATENT OFFICE.

JOHN NASH, OF BELLINGHAM, WASHINGTON.

DRAWING INSTRUMENT.

1,315,679.

Specification of Letters Patent.

Patented Sept. 9, 1919.

Application filed December 3, 1917. Serial No. 205,181.

To all whom it may concern:

Be it known that I, JOHN NASH, a citizen of the United States, residing at Bellingham, in the county of Whatcom and State of Washington, have invented a new and useful Drawing Instrument, of which the following is a specification.

It is one object of this invention to provide a simple but efficient instrument for laying off the teeth of gear wheels and for like purposes.

The invention aims to provide a novel form of right angled triangle, assembled in a novel way with a protractor.

It is within the province of the disclosure to improve generally and to enhance the utility of devices of that type to which the present invention appertains.

With the above and other objects in view which will appear as the description proceeds the invention resides in the combination and arrangement of parts and in the details of construction hereinafter described and claimed it being understood that changes in the precise embodiment of the invention herein disclosed can be made within the scope of what is claimed without departing from the spirit of the invention.

In the accompanying drawings:

Figure 1 shows in top plan, a drawing instrument constructed in accordance with the present invention, some of the graduations having been omitted; and

Fig. 2 is a section of the instrument shown in Fig. 1.

The instrument forming the subject matter of this application may be made of any desired material, and includes a protractor, denoted generally by the numeral 1, and comprising a base 2 and an arcuate arm 3. A lug 4 projects from the inner edges of the base 1, intermediate the ends of the base, and extends toward the arm 3 of the protractor. The arm 3 is marked off into semi-circular spaces 5, and into semi-circular spaces 6 and 7. The space 7 preferably is graduated, as shown at 8, to indicate degrees. The space 6, preferably has no graduations and serves to separate and distinguish the graduations 8 from graduations 9

individual to the spaces 5. Some of the graduations 8 and 9 have been omitted, for the sake of clearness, in the drawings. The spaces 5 are provided with different numbers of graduations 9. The innermost space 5 may be graduated into nine parts, and the outermost space 5 may be graduated into twenty-nine parts, the intermediate spaces 5 being graduated as desired.

Stops 10 are secured as shown at 11 to the protractor 1 at the ends of the base 2. The stops 10 may be marked, as shown at 12, with the numerals zero and 180, for use in connection with the graduations 8. The numeral 14 denotes a right angled triangle, the legs of which are offset as shown at 15 to receive the arcuate arm 3 of the protractor 1. At its right angle, the triangle 14 has an extension 16 which overlaps the base 2 of the protractor 1. A reinforcing plate 17 is superposed on the extension 16 and has a wing 18 overlapping the body portion of the triangle 14, the wing 18 being secured as indicated at 19 to the body of the triangle, and the plate 17 secured as indicated at 20 to the extension 16 of the triangle.

The numeral 21 denotes a clamp screw, one end of which is fixed in the base 2 of the protractor 1. The clamp screw 21 passes through registering arcuate slots 22 formed in the extension 16 of the triangle and in the reinforcing plate 17. A nut 23 is threaded on the screw 21 and is adapted to be clamped down on the reinforcing plate 17. The numeral 24 denotes a tubular pivot screw including a hub 25 on which the reinforcing plate 17 and the extension 16 of the triangle 14 are mounted to swing, the hub having a reduced end 26 secured in the lug 4 of the base 2 of the protractor 1. A nut 27 is threaded on the tubular pivot screw 24 and cooperates with the reinforcing plate 17 to hold the triangle 14 on the pivot screw for swinging movement. The nut 27 is retained by a lock nut 28 threaded on the pivot screw 24. A second screw 29 is threaded into the tubular pivot screw 24 and includes a center point 30. Near the fiducial edges 34 of the legs of the right angled triangle 14, the offset portions 15 of

90

95

100

the triangle are provided with zero marks 31 coöperating with the space 7, with ninety degree marks coöperating with the space 6, and with numerals 33, denoting how many 5 of the graduations 9 there are in each of the spaces 5. The triangle 14 includes a curved inner edge 35 coacting with the curved periphery of the arm 3 of the protractor 1 and carrying a vernier scale 36 10 coöperating with the graduations 8.

In practical operation, the triangle 14 may be swung on the pivot screw 24, the screw 29 being advanced so that the point 30 thereof may exercise its well known function. When the triangle 14 is swung on the 15 pivot screw 14, the clamp screw 21 moves in the registering slots 22 of the parts 17 and 16. By tightening down the nut 23, the triangle 14 may be held in any position to 20 which it may have been swung.

The fiducial edges 34 of the legs of the triangle may be used in connection with the graduations 8 or with the graduations 9. When the graduations 8 are used, the vernier 36, coöperating the graduations 8 gives 25 a closer reading of the angle than that defined by the graduations 8. When the edges 34 of the triangle come into abutment with the stops 10, alternately, one of the said 30 edges 34 may be used, in connection with the fiducial edge 37 of the base 2 of the protractor, to lay off a right angle. The edges 34 may be used in connection with the 35 various graduations 9, to lay off gear teeth, and the numeral 33 direct the attention of the operator to the proper space 5 to be used when it is desired that the gear wheel shall have a specified number of teeth. The fiducial edge 39 of the hypotenuse of the right 40 angled triangle 14 may be used for drawing inclined lines with respect to the lines determined by the fiducial edges 34, and for many other purposes. There may be openings 38 in the triangle 14, to facilitate the 45 hanging up of the instrument, to aid the operator in drawing small circles, and for

other purposes which will suggest themselves readily to the user.

Having thus described the invention what is claimed is:—

1. In a drawing instrument, a protractor comprising a base, and an arcuate arm having graduations; a right-angled triangle the legs of which define fiducial edges coöperating with the graduations, the triangle being provided, at its right angle, with an extension overlapped on the base and supplied with an arcuate slot, the legs of the triangle being offset to receive the arm, thereby to permit the outer portion of the triangle to be disposed in a common plane with the arm; a pivot element connecting the extension with the base; a stud on the base and extended through the slot; and a clamping device on the stud and coöperating with the 65 extension.

2. In a drawing instrument, a protractor comprising a base, and an arcuate arm having graduations; a right-angled triangle the legs of which define fiducial edges coöperating with the graduations, the triangle being provided at its right angle, with an extension overlapped on the base; a reinforcing plate secured to the extension of the 70 triangle and secured to the body of the 75 triangle, the plate and the extension having an arcuate slot; a pivot element mounted in the base and passing through the plate and the extension; a stud carried by the base and passing through the slot; a holding means on the pivot element and coöperating with the plate; and a clamping device on the stud and coöperating with the 80 plate.

In testimony that I claim the foregoing 85 as my own I have hereto affixed my signature in the presence of two witnesses.

JOHN NASH.

Witnesses:

W. M. GROW,
MARGARET GIDEON.
